RAZOR MOTOR CASING

Peter C. Neilson, Chicago, Ill.

Application December 14, 1946, Serial No. 716,250

3 Claims. (Cl. 172—126)

1

The present invention relates to an electric razor of the type commonly known as a wet razor wherein the razor head is of the safety razor type. The razor casing accommodates a motor that actuates the head causing vibration thereof. The user of such a razor first softens his beard with warm water and shaving soap or cream and then the vibrating head of the razor is brought in contact with the user's face and the beard is removed in a manner similar to that employed with a conventional safety razor. The vibration of the head provides a cutting action that greatly increases the efficiency of this type of razor over that of the conventional safety razor.

One object of the present invention is to provide such an electric razor wherein the motor is firmly held in the casing in such a manner that water is prevented from entering the casing and coming in contact with the motor parts. At the same time there is a complete elimination of screws and the like penetrating the casing. In prior razors of this type the motor is held in the casing by means of screws that pass through the casing and the exposed heads of these screws are constant sources of difficulty, both in allowing water to pass through the casing and coming in contact with the motor parts, and further these screw heads provide constant sources of electric shock to the user of the razor. In addition to this difficulty users of prior electric razors of this type are constantly subjected to electric shock when the head of the razor comes in contact with the user's face. This is due to the fact that in prior razors water is allowed to seep through the casing from the head thereof so as to cause a short in the electric circuit, thereby charging the razor head with an electric charge. This difficulty is completely eliminated in the razor forming the subject matter of the present invention by an effective grommet at the head end of the razor.

The present invention provides a sturdy razor of the type described wherein vibration of the casing itself is reduced to a minimum.

Further objects and advantages of the invention will become apparent from the following description and the drawings, in which

Fig. 1 is a longitudinal sectional view through the razor, the head of the razor being shown mostly in elevation;

Fig. 2 is a longitudinal vertical sectional view taken through the razor shown in Fig. 1, the head of the razor being shown in elevation;

Fig. 3 is a transverse sectional view through

2 the razor, the view being taken on the line 3—3 of Fig. 1;

Fig. 4 is a transverse sectional view through the razor, the view being taken on the line 4—4 of Fig. 1; and

Fig. 5 is a longitudinal sectional view, the view being taken on the line 5—5 of Fig. 1.

For purposes of illustration a single embodiment of the present invention has been selected, it being recognized however that many modifications may be made in the embodiment shown without departing from the intended scope of the invention.

Referring to the drawings the invention is illustrated in the form of a razor generally indicated at 10 that comprises a casing generally indicated at 11 and a head generally indicated at 12. The casing 11 comprises a cylindrical portion 13 that tapers as at 14. The opposite end 15 of the casing 11 is open and is provided with a flange portion 15 that abuts against a shoulder 16 on an end cap 17 that closes the open end of the casing 11.

Mounted in the casing 11 is a motor generally indicated at 18. This motor 18 includes a magnetic core member 19 that is substantially in the shape of an E that includes a pair of spaced arms 20 and 21 and a central arm 22. Disposed about the central arm 22 is an electromagnetic coil 23 that is adapted to be connected to a source of electrical current by means of wires 24 and 25 that pass through an aperture 26 in the end cap 17. As shown in Fig. 2 the core 19 may be made up of a plurality of laminated plates 19a.

An armature 27 is provided at one end with an up-turned portion 28. As shown in Fig. 2 a pair of arms 29 and 30 are welded to the up-turned portion 28 of the armature 27 so as to form in effect a C member that is adapted to straddle one end of the core 19. A rivet 31 passes through the arms 29 and 30 of the C member and through the laminated core 19 so as to secure the C member and the armature 27 to the core 19. A pair of spaced machine screws 32 pass through the up-turned portion 28 of the armature 27 and are forced against the end of the core 19 so as to make the up-turned portion 28 of the armature 27 rigid with respect to the core 19. The opposite end of the armature 27 is provided with an up-turned portion 33 that is apertured at 34 to receive a stud end 35 of a post 36. The post 36 is electrically insulated from the armature 27 by means of insulation indicated at 37. The stud end 35 of the post 36 is threaded to receive a

nut 38. The free end of the post 36 is provided with a flange 39 to which is secured the razor head 12 that may be of any conventional type. For purposes of illustration the head 12 is shown as comprising a razor blade supporting member 40, a razor blade 41 and a blade hold-down member 42. Thus head 12 may be threaded into the post 36 as indicated at 43.

Surrounding the post 36 is a grommet 44 made of rubber or some such suitable material that is adapted to seal the opening in the head end of the casing 11. This grommet 44 is provided with a lower sealing skirt portion 45 that is adapted to rest against the inner face of the tapered portion 14 of the casing 11. Adjacent to this lower skirt like portion 45 is a flared portion 46 that is provided with a shoulder 47 that engages the end of the tapered portion 14 of the casing 11. The outer extremity of the shoulder 47 conforms with the outer peripheral surface of the tapered portion 14 of casing 11. The outer end of the grommet 44 abuts against the shoulder 48 that is provided on the inner side of the flange 49. Thus the grommet 44 provides an effective seal so as to prevent passage of water from the head end of the razor into the interior of the casing 11.

As shown in Figs. 3, 4 and 5 the casing 11 is provided with a rectangular groove 49 along the top inner surface thereof and this groove extends substantially the full length of the casing and corresponds in width with the width of the core 19 of the motor. Thus the core 19 is adapted to fit into the rectangular groove 49 of the casing as indicated in Figs. 3 and 4 and thus be held against lateral movement in the casing. Adjacent to the bottom of the core 19 are a pair of spring like casing engaging members 50 and 51 secured respectively to arms 20 and 21 of the core 19. The engaging member 50 is substantially U-shape as indicated in Fig. 3 and is secured to the arm 20 of the core 19 by means of a bolt 52 on the end of which is threaded a nut 53. Likewise the engaging member 51 is substantially U-shape and as shown is secured to the arms 29 and 30 of the C member by means of welding or the like. These casing engaging members 50 and 51 are so arranged that they rest against the lower inner face of the casing 11 when the motor is enclosed in the casing and the core 19 is pocketed in the groove 49. A pair of guide strips 54 and 55 (Fig. 3) are provided along the lower inner face of the casing 11 at least in the forward part of the casing, and these guide strips are spaced to conform with the width of the casing engagement member 50 so as to guide the casing engagement member 50 and hold the lower end of the core 19 against lateral movement in the casing.

The end cap 17 is provided with a plug like portion 56 that is adapted to enter the casing 11 and an upstanding projecting portion 57 is provided along the upper edge of this plug like portion 56, this upstanding portion being adapted to fit snugly in the groove 49.

Thus is provided a razor of the type described that has a casing entirely free of penetrating screws and the like. The motor 18 is retained

rigidly in the casing through the armature 27 is free to vibrate up and down about its rear rigid connection to the core 19. This vibration is caused by the alternate changing of the polarity of the free end of arm 20 on the core 19. This action results from the change of field direction induced by the operation of the electromagnetic coil 23 in response to an alternating current. This vibrating movement of the armature 27 is in effect a very rapid backward and forward movement in one plane in a lateral direction parallel to the edge of the razor blade 41.

I claim:

1. A razor of the class described comprising an elongated casing having an open end, a motor in the casing adapted to slide through the open end of the casing, and means holding the motor fixed in the casing without penetrating through the walls of the casing including a groove in the inner face of the casing, means on the motor adapted to fit in the groove, and casing engaging means on the opposite side of and fixed to the motor and slidably engaging the inner face of the casing so as to hold the motor in fixed position in the casing.

2. A razor of the class described comprising an elongated casing having an elongated inner chamber of substantially circular cross section, the casing having an open end, a longitudinal groove in the wall of the chamber, a motor in the casing adapted to slide through the open end of the casing and having a longitudinal projecting portion adapted to project into the groove, and an arcuate engaging member on the motor on the side opposite the projecting portion adapted to engage the wall of the chamber.

3. A razor of the class described comprising an elongated casing having an elongated inner chamber of substantially circular cross section, the casing having one end open and the other end provided with a hollow elongated boss-like portion, a longitudinal groove in the wall of the chamber extending from the open end, a motor in the casing adapted to slide through the open end of the casing and having a longitudinal projecting portion adapted to project into the groove, one end of the motor being provided with an elongated shaft that is adapted to project through the boss-like portion and on its free end to receive a razor head, and an arcuate engaging member on the motor on the side opposite the projecting portion adapted to engage the wall of the chamber.
